US00D781742S

(12) United States Design Patent (10) Patent No.: US D781,742 S
(45) Date of Patent: * Mar. 21, 2017

(54) SLIDER FOR ARTICLE OF JEWELRY

(71) Applicant: Alex & Ani, LLC, Cranston, RI (US)

(72) Inventor: Carolyn A. Rafaelian, Cranston, RI (US)

(73) Assignee: Alex and Ani, LLC, Cranston, RI (US)

() Term: 14 Years

(21) Appl. No.: 29/511,632

(22) Filed: Dec. 12, 2014

(51) LOC (10) Cl. 11-01

(52) U.S. Cl.

USPC D11/87

(58) Field of Classification Search

USPC D11/1-2, 7, 40-44, 46-49, 53, 56, 57,
D11/59-61, 63, 65, 79-83, 86-87, 89-90,
D11/91-92, 99, 101, 106, 114-116,
D11/200-201; 63/18-20

CPC A44C 5/02
